UNITED STATES PATENT OFFICE

168,443

CHEST

Merton L. Gershun, Martinsville, Va., assignor to
American Furniture Company, Martinsville, Va.

Application January 29, 1952, Serial No. 18,288

Term of patent 7 years

(Cl. D33—6)

To all whom it may concern:

Be it known that I, Merton L. Gershun, a citizen of the United States, residing at Martinsville, in the county of Henry and State of Virginia, have invented a new, original, and ornamental Design for a Chest, of which the following is a specification, reference being had to the accompanying drawing forming a part thereof.

Fig. 1 is a perspective view of a chest showing my new design.

Fig. 2 is a broken perspective view showing the ornamental configuration of the front panel of the chest on a substantially enlarged scale.

The characteristic feature of my design resides in the front panel of the chest.

I claim:

The ornamental design for a chest, substantially as shown and described.

MERTON L. GERSHUN.
